UNITED STATES PATENT OFFICE.

FRANK A. GOODROW AND EDWARD F. GOODING, OF ELGIN, ILLINOIS.

BLASTING-PLUG.

971,264.

Specification of Letters Patent. Patented Sept. 27, 1910.

Application filed June 6, 1910. Serial No. 565,206.

To all whom it may concern:

Be it known that we, FRANK A. GOODROW and EDWARD F. GOODING, both citizens of the United States, and both residing at 5 Elgin, in the county of Kane and State of Illinois, have invented certain new and useful Improvements in Blasting-Plugs, of which the following is a specification.

At the present time, it is customary, in 10 blasting operations, to close the hole into which the blasting charge has been placed, by means of clay, sand, mud, stones or other convenient debris, allowing the fuse to project out through said closure. There are a 15 number of very serious objections to closing the blasting hole in this manner, among which is that the fuse is often injured in the closing operation, and the closure is not as dry as desired; but above all the closure 20 is not as secure and gas-tight as it should be. Very often these closures are blown out of the hole when the explosion takes place and serious injury has followed such an accident. This is because the direction of the 25 explosive force depends largely upon the resistance to be overcome, and when a closure blows out the explosive forces may be exerted in a direction wholly unexpected. The effectiveness of the explosion is largely determined by the amount of gas pressure 30 which may be generated in the charge chamber. It is evident that the greater the security of the closure the greater will be the gas pressure generated, and therefore the 35 greater the efficiency of the explosion.

The objects of this invention are, to provide a blasting plug which may be easily placed in the hole after the charge has been located; to provide a blasting plug which 40 shall securely resist blowing out; one which shall have the highest efficiency in holding up the gas pressure by preventing leakage; one which may be placed without danger of injuring the fuse; one which may be cheaply 45 manufactured; one which may be made in standard sizes; and one which shall comprise the fewest possible number of parts and shall be of small weight.

Other objects and features will appear 50 from a detailed description of the invention, which consists in the features of construction and combination of parts hereinafter described and claimed.

In the drawing, Figure 1 is a longitudinal 55 section of the blasting chamber, showing a charge of explosive laid in position, the ex-

plosion chamber being closed by one of our improved blasting plugs, and the fuse projecting through said plug; Fig. 2 is a detailed longitudinal section of one of the improved plugs, located in the hole and showing, in dotted lines, the manner in which the plug acts to jam the segments out against the sides of the hole when the blast pressure is created; Fig. 3 is a detailed cross section, 60 taken on line 3—3 of Fig. 2, looking in the direction of the arrows; Fig. 4 is a detailed cross section, similar to Fig. 3, the segments being in expanded position, such as they would occupy when the plug was forced out- 65 ward by the explosion; Fig. 5 is a side view of the plug; and Fig. 6 is a side view of one 70 of the segments, showing the groove into which may be placed the rubber band or other securing means used for loosely holding the segments in position around the 75 plug.

Referring to the figures, the device comprises a plug 7, having an annular body portion 8 of tapered formation, the body portion being provided with forward and rear end flanges 9 and 10 respectively, and with a fuse hole 11. This body portion may be of brass or cast iron, or any other suitable metal or material. Between the end 80 flanges 9 and 10, we provide a plurality of annular segments 12 of a shape and size to fit around the tapered portion 8. These segments are of such size and shape that when pushed down adjacent to the flange 9 at the 85 small end of the tapered body 8 they will set together in the manner shown in Fig. 3, but so that when shoved up toward the flange 10 onto the larger portion of the tapered body 8 they will occupy a position 90 similar to that shown in Fig. 4. Evidently these segments will be expanded or contracted in the same manner if they are held stationary and the plug 8 is moved. These 95 segments may be provided in their outer faces 13 with grooves 14, so located that when the segments are set together on the tapered portion 8 these grooves may align, so that a rubber band 15 or other flexible retaining material may be used to hold them 100 in proper position around the body portion. 105

In Fig. 1, the blasting charge is shown at 116 as located in a hole 17 drilled in the rock 18. The blasting charge 16 is provided with a fuse 19, which may pass through the hole 111 of the plug to the exterior of the blasting 110 chamber.

Referring to Fig. 2, it is seen that when a force is applied in the direction of the arrows 20 the tapered plug 8 will be forced out, while the segment 21, which lies against the bottom of the hole, will be held back by the friction on the hole. This segment will also act to hold the other segments back, by reason of the flexible manner in which they are held together, as by the rubber band. 5 When the tapered plug has been thus forced out a certain amount, the several segments will be expanded enough to bring them all into contact with the sides of the hole, and thereafter they will jam tighter the greater 10 the force exerted on the plug 8. In other words, when the explosion takes place a blow will be delivered against the inner end of the plug 8, which will thereupon be driven out until the segments have been forced into 15 contact with the wall of the hole around its entire periphery, and thereafter an increase of the blast pressure will merely serve to tighten the plug more and more, thus securely resisting blowing out and largely 20 preventing leakage of gas.

In order to insure greater reliability of action, the segments should be of a width such that they will hold the body portion of the plug up high enough so that the flanges 25 9 and 10 do not strike the lower side of the hole. When this is the case, there will be ample friction between the lower segment and the bottom of the hole to insure that the segments will be held back while the plug 30 is driven forward. However, in any case, if the band 15 is sufficiently flexible, the lower segment 21 will lie on the bottom of the hole, thus insuring that it will have sufficient friction to hold back while the plug 35 is driven forward. Evidently the exact taper of the plug 8 may be adjusted to give the most satisfactory results, depending upon the friction between the segments and the sides of the hole and the relative friction 40 between the materials of the plug and the segments. Also the number of segments used will depend largely upon the size of 45 the blasting hole.

In operation it is evident that the charge 50 16 may be inserted in the hole and then the plug 8, with the segments surrounding it, may be inserted over the fuse, which will project out through the hole 11. When pressing the blasting plug back into the 55 hole, such pressure will be exerted on the end of the plug having the small taper. Therefore, the segments will not jam, for they will be held back against the flange 9, and the plug can be easily inserted any 60 required distance by merely pressing against its outer end.

It is found that a blasting plug of this type is remarkably efficient in service, for

practically the only leakage of gas which can occur will be through the fuse hole 11 and 65 a slight amount past the segments 12. Also all danger of blowing out the plug is obviated, for the reason that the greater the explosive pressure the greater will be the grip of the plug on the hole. It is evident 70 that a blast will drive out the plug 8 so quickly that the segments will not be moved appreciably, thus insuring that the above described locking action shall occur. In other words, it is not even necessary that 75 the segments should be originally in frictional contact with the sides of the hole, although this is preferable.

We claim:

1. In a device of the class described, a 80 tapered body plug, and a plurality of segmental sections of equal width and of a form to encircle the tapered body portion, and together present a substantially circular periphery, the tapered body portion 85 being provided with a longitudinal fuse hole, and being further provided with end flanges, and means for retaining the segmental sections in position around the tapered body portion, substantially as de- 90 scribed.

2. In a device of the class described, a body portion comprising a tapered plug provided with substantially circular forward and rear end flanges, and provided 95 with a longitudinal fuse hole, and a plurality of segmental sections of a form to contact the wedge-shaped body portion and together present a substantially circular periphery, the diameter of the forward and 100 rear end flanges being substantially less than the diameter of the segmental sections when at the smaller end of the tapered plug portion, whereby when the device is placed in a hole with the segmental sections at the 105 smaller end of the body portion the end flanges may not contact the lower wall of the hole, substantially as described.

3. In a device of the class described, a body portion comprising a tapered conical plug provided with a longitudinal fuse hole and with forward and rear end flanges of substantially circular cross section, and a plurality of segmental sections of equal width adapted to encircle the tapered plug 110 and together present a substantially circular peripheral surface substantially parallel to the axis of the body portion, and means for retaining said segmental sections in position around the tapered plug portion, sub- 115 stantially as described.
